UNITED STATES PATENT OFFICE.

HUBERT BEDDOES AND JAMES W. COX, OF CHICAGO, ILLINOIS, ASSIGNORS TO PACIFIC FLUSH TANK COMPANY, OF CHICAGO, ILLINOIS, A CORPORATION OF ILLINOIS.

DOSING-TANK SYSTEM.

Application filed December 18, 1924. Serial No. 756,717.

The dosing tank systems to which our invention relates are commonly used in connection with sewage disposal for the purpose of distributing liquid material to filter beds, 5 the tank or tanks employed filling relatively slowly from the source of supply until a predetermined level of liquid is reached therein and then emptying rapidly by siphonic action by reason of which the liquid is more 10 thoroughly distributed to all parts of the filter or contact beds than would be the case were it fed thereto in the smaller stream flowing continuously from the settling tank or other source of supply. It has been 15 found advantageous in some cases to use a pair of dosing tanks operating alternately and our present invention applies to a system of this character. In order that the siphonic action in tanks of this character, 20 and particularly where a limited fall is available, shall be as positive and certain as possible they have heretofore in some instances been equipped with means for shutting off the feed thereto in the course of the dis- 25 charge of their contents and a means adopted for accomplishing this result without the use of moving parts has been a so-called air lock by means of which a pocket or cushion of air is interposed in the feed to the dosing 30 tank at the proper time to interrupt the flow of liquid to the tank, the supply of air to the air lock being controlled and furnished by a compression chamber provided 35 for that purpose. In the prior constructions of this character it has been necessary to provide a separate compression chamber for each dosing tank. Our invention provides for the operation of the air locks in both 40 of the dosing tanks of a system comprising 45 a pair thereof by means of a single compression dome common to the two tanks. Other features and advantages of the invention will be set forth in the following description and claims, it being understood however that 50 the specific disclosure is for the purpose of exemplification only and that the scope of the invention is defined in the claims in which we have endeavored to set forth as broadly as the state of the art known to us 55 will permit.

In the drawings Fig. 1 is a plan view of a dosing tank system involving our invention; Fig. 2 a vertical section thereof, partly shown in elevation and Fig. 3 a view of a 60 slightly modified detail.

Referring first to Figs. 1 and 2 of the drawings the dosing tanks are shown at 3, 3 with the compression dome 4 between them, this arrangement being convenient but not essential. The construction of the dosing tanks is identical and therefore the description of one will suffice for both. Each tank is provided with a siphon 5 arranged in the bottom thereof, the longer leg 6 of the siphon being connected to a union 7 from which the discharge pipe 8 carries the liquid to the filter bed or other place of disposal. A riser 9 connected to the union enters the bottom of the compression dome 4 above mentioned and one-way valves 13 are interposed between the siphon legs 6 respectively and the union so as to prevent up or back flow into the siphons. 60 65 70

The siphons may be of any known and suitable construction and we have illustrated a known type thereof, in which the bell 10 is provided with a vent 11 for breaking the siphon when the liquid in the tank has fallen to a predetermined point and a blow-off trap 12 by which the siphon is put 80 into operation, these features of the construction shown being well-known to those skilled in this art. The inlet end of each dosing tank is divided from the body of the tank by a dam 15 and is provided with a partition 16 dividing the inlet tank into the chambers 17 and 18, the former of which is connected to the inlet 14. The partition 16 is somewhat higher than the dam 15 and a feed opening therein is occupied by a casting 19 which provides a generally U-shaped passage for the liquid through the partition. The casting or feed bell 19 is air tight save for the pipes 20 and 21, the former of which supplies air to the bell or air lock and the latter releases the air therefrom in the conditions hereinafter described. 85 90 95

The compression dome 4 is provided with a vent 22 extending above the maximum level of liquid in the tanks and preferably opening into the latter at branches 23. The vent 22 projects through the top of the compression dome downwardly into the latter a sufficient distance to provide an air trap or chamber in the compression dome of sufficient capacity for providing the amount of air required for the operation of the air locks. An air pipe 26 extends upwardly from the top of the compression dome and is branched at 27, the branches leading to 100 105 110

the respective air supply pipes 20 for the air locks. With each discharge of either dosing tank a portion of the liquid therefrom is forced up the riser 9 into the compression dome and into the vent 22 to a level somewhat below that of the liquid in the emptying tank and sufficiently high to put the required amount of pressure on the air trapped in the compression dome above the lower end of the vent. In order that the air from the compression dome may go only to the air lock controlling the feed to the tank which is being discharged, each of the branch pipes for conveying the air to the respective locks is formed with a U-shaped switch trap 29 which dips or depends into the tank other than that with the air lock of which it is connected. In other words the branch for supplying the left hand air lock, as seen in the views, is formed with a trap depending into the right hand tank and the branch for supplying the air lock of the right hand tank is provided with a trap depending into the left hand dosing tank. A U-shaped liquid inlet pipe 30 opens into each of the switch traps 29, the other end of the pipe 30 being open to the liquid in the tank in which it is located. When either tank is approximately full of liquid a column of liquid rises in the trap 29 located therein a sufficient distance to effectively resist the air pressure from the compression dome and thus shut off the air from the air lock of the other tank. On the other hand when the level in the tank is low the trap therein is substantially or completely void of water and consequently the air from the compression dome can flow through said trap to the air lock connected therewith. Thus during the earlier and major portion of the discharge of either tank, or, it may be substantially throughout such discharge, depending on the design, air is supplied to the air lock thereof from the compression dome while at the same time the supply of air to the air lock of the other tank is cut off.

As heretofore stated the pipe 21 provides for the escape of the air from the air lock when the feed to the dosing tank is to be resumed after the discharge thereof has been completed, and the other tank has commenced to discharge. It is necessary, however, in order that the air lock may operate as such that the escape of air through the pipe 21 is prevented until the emptying of the tank is completed. For this purpose pipe 21 is carried downward to near the bottom of the dosing tank at 40 and connected to a riser 41 to form a blow-off trap 60 which fills with liquid when the tank is filled and remains filled, thus sealing pipe 21, even after the liquid in the tank has been discharged and until the trap is emptied by the means to be now described. A bell 42 within the compression dome, and extending nearly to

the bottom thereof, is connected by a pipe 43 with a pair of branch pipes 44 leading to the bottoms of the respective traps 60. As seen at the right in Fig. 2, when the liquid from the discharge of one of the tanks enters the compression chamber it compresses the air within the bell 42 therein and forces it up the pipe 43. Because of the depth of the liquid in the tank which is starting to discharge the air cannot escape through the feed blow-off trap therein. At this time, however, the feed blow-off trap in the other tank is uncovered and the air from the pipe 26 being under sufficient pressure for the purpose enters the bottom of pipe 41 in said empty tank and discharges the liquid therein. This clears the way for the air from the corresponding air lock to escape from pipe 21 through said riser 41, leaving said air lock unobstructed for the passage of liquid therethrough. The liquid from the inlet then flows through the air lock and spills over the dam into the tank filling the same.

The only essential difference between the modification of the apparatus shown in Fig. 3 and that just described is that in the former the bell 42 is omitted, the pipe 45' being prolonged a suitable distance so that shortly after it has received the air necessary to discharge the feed blow-off trap it is sealed against further escape of air.

The operation of the various parts of the device has been described in connection with the construction thereof but the operation of the system as a whole may now be described as follows: The conditions represented in Fig. 2 of the drawings are those that exist after the right-hand tank has been emptied and the left-hand tank has just begun to discharge. As there shown, the feed blow-off trap and switch trap in the left-hand tank are submerged, shutting off the flow of air therethrough and the feed blow-off trap and switch trap in the right-hand tank are exposed. The liquid has mounted in the riser 9, compression dome 4 and vent 22. The air in bell 42 in the compression dome has been compressed and is clearing the exposed feed blow-off trap in the right-hand tank, and the air in the corresponding feed air lock has begun to exhaust through the riser 41 in the empty tank. Air is beginning to flow into air lock 19 of the left-hand tank from the compression dome, being cut-off from the right hand air lock by the switch trap in the left hand tank. During the initial part of the discharge of the siphon in the left-hand tank sufficient air is driven over from the compression chamber to the air lock controlling the admission of liquid to said tank to force down the liquid level in said lock sufficiently to cut-off liquid flow therethrough. As the liquid level in the inlet tank is maintained

by the dam 15 the air lock remains closed until the air is released therefrom through the corresponding feed blow-off trap 16 in the manner heretofore described, which only 6 takes place, however, when the right-hand dosing tank begins to discharge. In the meantime the right-hand dosing tank is filling and ultimately the liquid therein reaches a level at which it refills blow-off trap 41 10 and submerges switch trap 29, thus preventing the flow of air therethrough. In the meantime when the discharge from the left-hand tank ceases the liquid in the compression chamber drops down the riser 9, permitting said compression chamber to again 15 fill with air. When the liquid in the right-hand tank reaches the predetermined level the contents of said tank begins to discharge through the siphon thereof and the operation just described is repeated except that 20 the functioning of the tank is reversed.

The operation of the system continues indefinitely and automatically.

We claim:

25 1. In a dosing system of the class described, a pair of dosing tanks, a siphon in each tank for discharging the same, a common compression chamber connected to the siphons, air locks controlling the feed 30 of liquid to the respective tanks, connections from the compression chamber for supplying air to both said air locks, and means for releasing the air from the air locks.

2. In a dosing system of the class described, a pair of dosing tanks, a siphon in each tank for discharging the same, an air lock controlling the feed of liquid to each tank, a common compression chamber connected to the discharge ends of the siphons, 40 connections from the compression chamber to the respective air locks for supplying them with air, a switch trap in the connection to each air lock, connections for closing said traps by liquid from the other 45 dosing tank, and means for releasing the air from the respective air locks.

3. In a dosing system of the class described, a pair of dosing tanks, a siphon in each tank for the discharge of liquid 50 therefrom, an air lock controlling the feed of liquid to each tank, a compression chamber connected to the outlets of both siphons, connections from the compression chamber to the respective air locks for supplying air 55 to the latter, a trap in the connection to the air lock of each dosing tank, open to the other dosing tank to be closed and opened by liquid therein, and means to discharge air from the respective air locks.

60 4. In a dosing system of the class described, a pair of dosing tanks, a siphon in each tank for the discharge of liquid therefrom, an air lock controlling the feed to each tank, a compression chamber connected 65 to the outlets of both siphons, connections

from the compression chamber to the respective air locks for supplying air to the latter, a U-shaped trap in each said connection depending into the other dosing tank and having an opening therein whereby the 70 liquid in the last said dosing tank may open and close said traps, and means to discharge air from the respective air locks.

5. In a dosing system of the class described, a pair of dosing tanks, a siphon in 75 each tank for discharging liquid therefrom, an air lock controlling the feed to each tank, a compression chamber connected to the outlets of both siphons, connections from the compression chamber to the respective air 80 locks for supplying air to the latter, a U-shaped trap in each said connection to the air lock of a dosing tank depending into the other dosing tank of the system, a U-shaped filling trap therefor open to said last-mentioned tank, and means to discharge air from the respective air locks. 85

6. In a dosing system of the class described, a pair of dosing tanks, a siphon in 90 each tank for discharging the liquid from the same, an air lock controlling the feed to each tank, a compression chamber connected to the outlets of both siphons, connections from the compression chamber to the respective air locks for supplying air to the latter, means controlled by the level of the liquid in one of said dosing tanks controlling the said air connections for the air lock of the other dosing tank, and means to discharge air from the air lock. 95

7. In a dosing system of the class described, a pair of dosing tanks, a siphon in 100 each tank for discharging liquid from the same, an air lock controlling the feed to each tank, a compression chamber connected to the outlets of both siphons, means for supplying the respective air locks with air, a passage for relieving each air lock of air, a connection from each dosing tank to the corresponding air passage whereby the liquid 105 in the dosing tank may close said air passage. 110

8. In a dosing system of the class described, a pair of dosing tanks, a siphon in 115 each tank, for discharging liquid from the same, an air lock controlling feed to each tank, a compression chamber connected to the outlets of both siphons, connections from the compression chamber to the respective air locks for supplying air to the latter, an air outlet pipe for each air lock, a feed blow-off trap in each said outlet pipe open to the corresponding dosing tank whereby said trap may be closed by the liquid from the dosing tank. 120

9. In a dosing system of the class described, a pair of dosing tanks, a siphon in 125 each tank for discharging the same, an air lock controlling feed to each tank, a compression chamber connected to the outlets of both siphons, connections from the compres-

sion chamber to the respective air locks for supplying air to the latter, an air outlet pipe for each air lock, a feed blow-off trap in said pipe, said trap being located in the 5 corresponding dosing tank and opening upward into to same whereby the trap may be closed by liquid in said tank.

10. In a dosing system of the class described, a pair of dosing tanks, a siphon in each tank for discharging the same, an air lock controlling feed to each tank, a compression chamber connected to the outlets of both siphons, connections from the compression chamber to the respective air locks 15 for supplying air to the latter, an air outlet pipe for each air lock, a feed blow-off trap in said pipe opening into the corresponding dosing tank, a connection from the compression chamber to said feed blow-off trap 20 whereby air from the compression chamber may be discharged through the trap to empty the same of liquid.

11. In a dosing system of the class described, a pair of dosing tanks, a siphon in each tank for discharging liquid from the same, an air lock controlling the feed to each tank, a compression chamber connected to the outlets of both siphons, connections from the compression chamber to the respective air locks for supplying air to the latter, switch

traps in the respective connections, a connection from each dosing tank to the air supply connection for the air lock of the other dosing tank whereby liquid from the first said tank controls the supply of air to the 35 other said tank, an air outlet pipe for each air lock, a feed blow-off trap in said pipe, and a connection from the corresponding dosing tank whereby the liquid therein controls the passage of the feed blow-off trap. 40

12. In a dosing system of the class described, a pair of dosing tanks, a siphon in each tank for discharging the same, an air lock controlling the feed to each tank, a compression chamber connected to the outlets of 45 both siphons, connections from the compression chamber to the respective air locks for supplying air to the latter, a trap in the connection to the air lock of each dosing tank, said trap being located in the other 50 dosing tank and arranged to be closed and opened by the liquid therein, an air outlet pipe for each air lock, a feed blow-off trap in said pipe located in the corresponding dosing tank, and a connection from the compression chamber to said feed blow-off trap 55 whereby air from said chamber may be discharged through the trap to empty the same.

HUBERT BEDDOES.
